UNITED STATES PATENT OFFICE.

JOHN F. APPLEBY, OF MINNEAPOLIS, MINNESOTA, ASSIGNOR TO THE
MINNEAPOLIS HARVESTER WORKS, OF SAME PLACE.

BUNDLE-CARRIER FOR HARVESTERS.

SPECIFICATION forming part of Letters Patent No. 362,141, dated May 3, 1887.

Application filed March 12, 1886. Serial No. 194,947. (No model.)

To all whom it may concern:

Be it known that I, JOHN F. APPLEBY, of Minneapolis, in the county of Hennepin and State of Minnesota, have invented certain Improvements in Bundle Carriers for Harvesters, of which the following is a specification.

This invention relates to improvements in the carriers that are used with self-binding harvesters to receive the bundles as they are discharged from the binding mechanism, and to drop them in windrows for convenience in shocking.

The invention consists, generally, in the construction and combination hereinafter described, and particularly pointed out in the claims.

In the drawings forming part of this specification, Figure 1 is a plan of a portion of a harvester with my invention applied thereto. Fig. 2 is an elevation of the carrier and a portion of the supporting and operating mechanism, looking in the direction of arrow 1 in Fig. 1. Fig. 3 is a partial elevation looking in the direction of arrow 2 in Fig. 1. Fig. 4 is a detail showing the spindle and inclined joint.

In the drawings, A represents the basket or carrier, which is secured beneath the binding mechanism B, substantially as shown in Fig. 1. This basket may be of any suitable construction. As shown, the basket is formed with a slatted bottom, 4, an open rear end, and inclined front and side walls, 6, 8, and 10. The wall 8, opposite the binding mechanism, is preferably higher than the others, so that the bundles are prevented from passing over it as they are thrown into the basket. The forward part of the basket as thus constructed is heavier than the rear part, bringing the center of gravity near the forward end.

I support the basket at a point substantially under its center of gravity upon a transverse journal or pivot, and when the basket is empty it is practically balanced upon this support and remains in a substantially horizontal position. As the bundles fall into the basket, the greater part of their weight is in the rear of this journal, and tends to tilt the basket thereon. I provide means under the control of the operator for holding the basket in a horizontal position until the point where the bun-

dles are to be deposited is reached, when the basket is allowed to tilt and dump the bundles. I have shown in the drawings preferable means for thus supporting and holding the basket.

A sleeve, 16, is supported by suitable braces, 18 and 20, from the harvester-frame and a shaft, 22, beneath the binding mechanism. In this sleeve is a spindle, 24, that is free to turn therein, but having its movement limited by a suitable stop-pin, 26, that encounters a projection on the end of the sleeve. This spindle is of L shape, the end nearest the basket being at right angles to the main part, and forming a journal, 30. A casting, 28, having a journal-bearing formed therein, is secured to the basket by bolts or other suitable means. This bearing fits upon the journal 30 and turns freely thereon. This construction allows the outer end of the basket to be raised, as indicated by dotted lines in Fig. 2, and the basket to be folded against the harvester for convenience in passing through a gateway or by an obstruction. The axis of this journal-bearing is at an angle to the bottom of the basket, as shown in Figs. 2 and 3. When the basket strikes an obstruction, it will turn on this inclined journal, moving backward and up, and unless the obstruction is too high will pass over it. A lug, 34, projects from the upper surface of the casting 28. A collar, 36, having a depending lug, 38, is secured to the shaft 22. A rod, 40, having crank-arms 42 44 formed upon its opposite ends, is supported in bearings formed in the lug 38 and in a projection, 46, secured to the front part of the harvester-frame. A connecting-rod, 50, extends from the arm 42 to the lug 34 on the casting 28.

The harvester is provided with the usual seat-support, 52, having a foot-rest, 54, thereon. A foot-rest, 56, preferably of substantially bell-crank-lever shape, is pivoted to a projection, 58, in a convenient position for the foot of the person seated upon the machine to rest upon the upper arm thereof. A connecting-rod, 60, extends from the other arm of the foot-rest to the crank-arm 44 on the rod 40.

It will be seen that when the basket is in a horizontal position, as shown by full lines in

100.

Fig. 3, the connecting-rod 50 is nearly in line with the crank-arm 42, so that a light pressure on the pivoted foot-rest, such as will be given by the operator's foot resting thereon, will prevent the weight of the bundles from tilting the basket. When the foot is raised from the foot-rest, the weight of the bundles will tilt the basket, the spindle 24 turning in the sleeve 16, and the bundles will slide to the ground. A light pressure on the foot-rest will then return the basket to a horizontal position.

The spindle 24, which forms the pivot or journal upon which the basket tilts, is located forward of the binding mechanism, as shown in Fig. 1, and the weight of the bundles in the basket is mainly in the rear of the pivot, and the basket is thereby turned on this pivot as soon as the operator releases the holding device.

I claim as my invention—

20 1. In a harvester, a bundle-carrier pivoted transversely to the line of advance of the machine, with an inclined joint between said carrier and the point of support upon the ma-

chine-frame, whereby said carrier may have an upward and backward movement about said inclined joint, substantially as described.

2. The combination, with a harvester-frame, of a laterally-projecting rock-shaft journaled in bearings on said frame and a sheaf-carrier secured thereto, the said shaft having an inclined joint at a point between the bearings on the frame and the point of attachment to the sheaf-carrier, whereby said carrier may be turned upward and backward on said joint.

3. The combination, with the sleeve 16, supported beneath the harvester-frame, of the spindle 24, mounted therein, the inclined journal 30 at right angles to said spindle, and the bundle-carrying basket having the inclined bearing mounted upon said journal, substantially as and for the purpose set forth.

JOHN F. APPLEBY.
